US00D921695S

(12) **United States Design Patent** (10) Patent No.: **US D921,695 S**
Okumura et al. (45) Date of Patent: ** Jun. 8, 2021

(54) **PORTION OF DISPLAY PANEL OR SCREEN WITH AN ICON**

(71) Applicant: **SONY CORPORATION**, Tokyo (JP)

(72) Inventors: **Mitsuo Okumura**, Tokyo (JP); **Katsuji Miyazawa**, Tokyo (JP); **Tomohiro Ishii**, Tokyo (JP); **Shingo Kurokawa**, Kumamoto (JP); **Yuki Shoji**, Tokyo (JP); **Osamu Sakurai**, Tokyo (JP); **Makoto Niijima**, Saitama (JP); **Taku Sugawara**, Tokyo (JP); **Sanae Hirai**, Tokyo (JP)

(73) Assignee: **SONY CORPORATION**, Tokyo (JP)

(**) Term: **15 Years**

(21) Appl. No.: **29/599,082**

(22) Filed: **Mar. 30, 2017**

Related U.S. Application Data

(63) Continuation of application No. 29/463,848, filed on Mar. 18, 2014, now Pat. No. Des. 786,930, which is a continuation of application No. 29/371,939, filed on Feb. 3, 2012, now Pat. No. Des. 703,694.

CLAIM

The ornamental design for a portion of a display panel or screen with an icon, as shown and described.

DESCRIPTION

FIG. 1 is a front view of a first embodiment of a portion of a display panel or screen with an icon showing our new design.

FIG. 2 is a front view of a second embodiment of a portion of a display panel or screen with an icon showing our new design.

FIG. 3 is a front view of a third embodiment of a portion of a display panel or screen with an icon showing our new design.

FIG. 4 is a front view of a fourth embodiment of a portion of a display panel or screen with an icon showing our new design.

FIG. 5 is a front view of a fifth embodiment of a portion of a display panel or screen with an icon showing our new design.

FIG. 6 is a front view of a sixth embodiment of a portion of a display panel or screen with an icon showing our new design.

FIG. 7 is a front view of a seventh embodiment of a portion of a display panel or screen with an icon showing our new design.

FIG. 8 is a front view of an eighth embodiment of a portion of a display panel or screen with an icon showing our new design.

FIG. 9 is a front view of a ninth embodiment of a portion of a display panel or screen with an icon showing our new design.

FIG. 10 is a front view of a tenth embodiment of a portion of a display panel or screen with an icon showing our new design.

FIG. 11 is a front view of an eleventh embodiment of a portion of a display panel or screen with an icon showing our new design.

FIG. 12 is a front view of a twelfth embodiment of a portion of a display panel or screen with an icon showing our new design.

FIG. 13 is a front view of a thirteenth embodiment of a portion of a display panel or screen with an icon showing our new design.

FIG. 14 is a front view of a fourteenth embodiment of a portion of a display panel or screen with an icon showing our new design.

FIG. 15 is a front view of a fifteenth embodiment of a portion of a display panel or screen with an icon showing our new design.

FIG. 16 is a front view of a sixteenth embodiment of a portion of a display panel or screen with an icon showing our new design.

FIG. 17 is a front view of a seventeenth embodiment of a portion of a display panel or screen with an icon showing our new design.

FIG. 18 is a front view of an eighteenth embodiment of a portion of a display panel or screen with an icon showing our new design.

FIG. 19 is a front view of a nineteenth embodiment of a portion of a display panel or screen with an icon showing our new design.

FIG. 20 is a front view of a twentieth embodiment of a portion of a display panel or screen with an icon showing our new design.

FIG. 21 is a front view of a twenty-first embodiment of a portion of a display panel or screen with an icon showing our new design.

FIG. 22 is a front view of a twenty-second embodiment of a portion of a display panel or screen with an icon showing our new design.

FIG. 23 is a front view of a twenty-third embodiment of a portion of a display panel or screen with an icon showing our new design.

FIG. 24 is a front view of a twenty-fourth embodiment of a portion of a display panel or screen with an icon showing our new design.

FIG. 25 is a front view of a twenty-fifth embodiment of a portion of a display panel or screen with an icon showing our new design.

FIG. 26 is a front view of a twenty-sixth embodiment of a portion of a display panel or screen with an icon showing our new design.

FIG. 27 is a front view of a twenty-seventh embodiment of a portion of a display panel or screen with an icon showing our new design.

FIG. 28 is a front view of a twenty-eighth embodiment of a portion of a display panel or screen with an icon showing our new design.

FIG. 29 is a front view of a twenty-ninth embodiment of a portion of a display panel or screen with an icon showing our new design.

FIG. 30 is a front view of a thirtieth embodiment of a portion of a display panel or screen with an icon showing our new design.

FIG. 31 is a front view of a thirty-first embodiment of a portion of a display panel or screen with an icon showing our new design.

FIG. 32 is a front view of a thirty-second embodiment of a portion of a display panel or screen with an icon showing our new design.

FIG. 33 is a front view of a thirty-third embodiment of a portion of a display panel or screen with an icon showing our new design.

FIG. 34 is a front view of a thirty-fourth embodiment of a portion of a display panel or screen with an icon showing our new design.

FIG. 35 is a front view of a thirty-fifth embodiment of a portion of a display panel or screen with an icon showing our new design.

FIG. 36 is a front view of a thirty-sixth embodiment of a portion of a display panel or screen with an icon showing our new design.

FIG. 37 is a front view of a thirty-seventh embodiment of a portion of a display panel or screen with an icon showing our new design.

FIG. 38 is a front view of a thirty-eighth embodiment of a portion of a display panel or screen with an icon showing our new design.

FIG. 39 is a front view of a thirty-ninth embodiment of a portion of a display panel or screen with an icon showing our new design.

FIG. 40 is a front view of a fortieth embodiment of a portion of a display panel or screen with an icon showing our new design.

FIG. 41 is a front view of a forty-first embodiment of a portion of a display panel or screen with an icon showing our new design.

FIG. 42 is a front view of a forty-second embodiment of a portion of a display panel or screen with an icon showing our new design.

FIG. 43 is a front view of a forty-third embodiment of a portion of a display panel or screen with an icon showing our new design.

FIG. 44 is a front view of a forty-fourth embodiment of a portion of a display panel or screen with an icon showing our new design.

FIG. 45 is a front view of a forty-fifth embodiment of a portion of a display panel or screen with an icon showing our new design; and,

FIG. 46 is a front view of a forty-sixth embodiment of a portion of a display panel or screen with an icon showing our new design.

The dot-dash broken lines in each figure show a portion of a display panel or screen. The dot-dash broken line in each figure defines the boundaries of, but not included in, the claimed design. The evenly spaced broken lines illustrate the unclaimed environment of the claimed design and form no part thereof.
